CHARLES M. RAYNALE, OF BIRMINGHAM, MICHIGAN.

Letters Patent No. 61,020, dated January 8, 1867.

IMPROVED PROPELLER FOR VESSELS.

The Schedule referred to in these Letters Patent and making part of the same.

TO ALL WHOM IT MAY CONCERN:

Be it known that I, CHARLES M. RAYNALE, of Birmingham, in the county of Oakland, and State of Michigan, have invented a new and useful Improvement in the Mode of Propelling Vessels; and I do hereby declare that the following is a full, clear, and exact description of the same, reference being had to the annexed drawings, making part of this specification, in which—

Figure 1 is a perspective view of the stern of a vessel.

Figure 2 is a vertical transverse section; and

Figure 3, a perspective view of one of the plungers.

In all the figures I employ the same letters in the indication of identical parts.

A is the stern of a vessel; on each side of the vessel I place a chamber, B, opening directly astern. This tubular chamber extends horizontally within the hull and then turns at right angles upwards. The chamber being open at the lower extremity will be filled with water to the height of the external water line, the water rising in the vertical portion of the chamber. This part of the chamber is fitted to receive the plunger C, which is formed with an external case fitting the tube. This case sustains the valve C', which is hinged on one side to the case, and when closed forms a head for the plunger. This valve in closing shuts against the central partition C'', or may be made to work against proper valve seats in the lower edge of the case. The opening of the valve is limited by a stop, C'', which is represented as a bar attached to the case, and carried below the valve. The form of this stop is not important; any arrangement will be sufficient that stops the valve at such a point as will permit the water about the plunger to escape freely, and insure at the same time its prompt return to the valve seat, where the forward thrust of the plunger commences. These plungers may be worked by any convenient arrangement of the actuating mechanism. I have shown one form, viz., the connecting-rods attached respectively to the wrists of a double crank, D, so constructed that the plungers shall each alternately rise as the other descends. The water will fill part of the vertical portion of B B, and the reciprocating plungers pressing against the same will force the vessel forward with the expulsion of the column of water. As the plunger rises the inward pressure of the column of water will fill the chamber in front of the plunger. The opening valves as the plungers are raised will permit the escape of such water as may leak past the plunger.

I do not claim the propulsion of vessels by the forward thrust of a reciprocating plunger, acting directly against the water, for this I know has been already done. My improvements relate to cheapening and simplifying the construction of such propellers by bringing the chamber B upward so that the plungers could operate vertically and against the column maintained in the chambers at the height of the external surface. In a horizontal cylinder, closed, as it necessarily must be at the inner end, there is a resistance to the backward action of plunger from the leakage water in the forward end of the cylinder. In the vertical arrangement there is no resistance to the upward action of the plunger, and the outwardly opening valve prevents the plunger from acting as a pump to sustain the weight of the column of water following its action. I am thus able to operate the plungers with the minimum of resistance to their upward action.

What I claim as my invention, and desire to secure by Letters Patent, is—

A vessel constructed with pipes B B, opening directly astern, and bent at right angles upward, in combination with reciprocating plungers C, open above, and working vertically in each, said plungers being constructed with outwardly opening valves C', and arranged to operate substantially as and for the purpose set forth.

In testimony whereof I have signed my name to this specification in the presence of two subscribing witnesses.

CHARLES M. RAYNALE.
